UNITED STATES PATENT OFFICE.

RONALD F. McFEELY, OF BEVERLY, MASSACHUSETTS, ASSIGNOR TO UNITED SHOE MACHINE COMPANY, OF PATERSON, NEW JERSEY, A CORPORATION OF NEW JERSEY.

TACKING MECHANISM.

1,135,956.

Specification of Letters Patent. Patented Apr. 13, 1915.

Application filed October 3, 1910. Serial No. 585,069.

To all whom it may concern:

Be it known that I, RONALD F. McFEELY, a citizen of the United States, residing at Beverly, in the county of Essex and State 5 of Massachusetts, have invented certain Improvements in Tacking Mechanisms, of which the following description, in connection with the accompanying drawings, is a specification, like reference characters on 10 the drawings indicating like parts in the several figures.

This invention relates to machines for use in the manufacture of boots and shoes and particularly to nailing or tacking apparatus 15 used in such machines.

The invention is shown for exemplification as embodied in a pulling-over machine of the type shown in the prior Patent No. 663,777 granted on my application December 11, 1900, but protection is sought for 20 all uses for which this invention is adapted.

The general object of this invention is to provide for variations in the positions at 25 which tacks shall be inserted, and it may be also in the number of tacks driven.

A very important feature of the invention is found in the provision of means for changing the lateral position in which the toe tack is inserted. It is found in the use 30 of this pulling-over machine, and similar conditions might be met in other machines, that right and left shoes made on crooked lasts can be most satisfactorily secured at the toe by tacks driven in different relations 35 to the median line of the machine. Also in the commercial pulling-over machine the toe tacker is associated with a wiper to lay the upper in position to be secured and it is of advantage to adjust the path of the wiper 40 relatively to the median line of the machine so that it shall act uniformly to lay the upper into position to be secured.

In accordance with the preferred embodiment of this invention the tacker and wiper 45 are adjusted together, and also the toe gripper of the machine is adjusted in company therewith.

In accordance with another feature of this invention provision is made for adjustment 50 to vary the distribution of the tacks to the toe and side tackers. This feature of the invention solves the problem presented in factories making styles of shoes which require the upper to be secured at different points. 55 For example, shoes having short vamps re-

quire to be pulled and fastened by a tack close to the toe at each side of the last. When these shoes are made on lasts which have high or prominent toes and are relatively thin between the toe and the instep 60 the shoe requires to be pulled and fastened by a tack driven well back along the ball of the last. To meet these varying conditions, each side tacking mechanism of the machine is equipped, in accordance with a preferred 65 form of this invention, with the maximum number of drivers, tack holders and conductors which will at any time be required and the tack supplying and distributing mechanism is constructed and arranged to 70 deliver the whole number of tacks or a selected series of tacks. For this purpose novel means, which may be independent of the separating mechanism, is provided for stopping the delivery of tacks from selected 75 raceway grooves whereby a varying predetermined number and arrangement of tacks is delivered into position to be driven by the selected drivers.

These and other features of this invention, including certain details of construction and more important combinations of parts, will appear in connection with the following description of the illustrated machine and then will be pointed out in the 80 claims.

Figure 1 is a side elevation of a pulling-over machine equipped with the present improvements; Fig. 2 is a perspective view of the toe tack driving mechanism; Fig. 3 is 90 a perspective view of the tack distributing mechanism; Figs. 4, 5 and 6 are front views of the tack controlling mechanism in different positions of adjustment with accompanying diagrams to show the arrangement 95 of tacks in the shoe following from each adjustment; Fig. 7 is a side elevation of the adjusting devices.

The machine comprises the head 2 which is supported on a post and has bearings for 100 a shaft 4 from which is reciprocated a rack 5 that drives a tack lifter in the hopper 6. From the lifter the tacks gather in raceway grooves, Fig. 3, which are inclined downwardly toward the toothed separating slide 105 10 which, by reciprocatory movement across the ends of the raceways, takes a tack from each groove that is open and delivers it to the appropriate tack tube 12 by which it is conducted to its tack pocket in the side or 110

toe tacking mechanism. Each tacking mechanism includes, in addition to the tack block having tack pockets and conductors equal in number to the maximum number of tacks to be driven, a driver bar 14 with a like maximum number of drivers 15. These parts in general may be substantially as in said prior Patent No. 1,030,522.

The raceway block 20, Fig. 3, which for the purpose of this description may be considered as a single member with tack grooves therein, is cut away at its lower end above the separator slide 10 and its coöperating parts to receive plates 22, 23 that have passageways 24 cut through them in position for alinement, respectively, with the first and second and the sixth and seventh raceway grooves. The upper portions of the opposed lateral walls forming the sides of the passageways 24 are extended inwardly as fingers 24^a located below the tack head supporting surfaces of the raceway block in position to be projected transversely across the tack grooves in the path of the tack stems as may be seen from the illustration in Figs. 4, 5 and 6. This embodiment of the invention therefore, presents a tack controller 22, 24^a, 24^b for the first and second tack grooves which is located on the left side of the first groove and on the right hand side of the second groove, and a similarly arranged controller 23, 24^a, 24^b for the sixth and seventh grooves, the lower wall of the passageway being located below the stems of the tacks in the grooves where it extends across the grooves and the intervening structure of the block 20. The plates have overlapping ends both of which are operatively connected with an adjuster 25 which can be rotated by a screw threaded block that is adapted to be turned by the tool 26 through an angle and in directions appropriate to separate the plates farther (Fig. 6) from their normal relation, Fig. 4, or to draw them closer together, Fig. 5. The passageways 24 are so proportioned and located relatively to the raceway grooves that when the plates are in the central position, Fig. 4, all the raceway grooves are open and tacks will be separated and fed for insertion as indicated in the diagram that is below Fig. 4. When the plates 22, 23 are drawn closer together by the manipulation of the adjuster as represented in Fig. 5 the plates close the first and seventh raceway grooves and permit the delivery of only five tacks and these tacks are the ones which go into tubes associated with drivers that insert them in the relation shown in the Fig. 5 diagram. When the adjuster is shifted to the position shown in Fig. 6 the plates 22, 23 are separated and close the second and sixth raceway grooves thereby cutting out the intermediate tack as in the Fig. 6 diagram. By this means different predetermined numbers and arrange-

ments of tacks can be secured without changing the running parts of the machine.

To prevent liability of unauthorized tampering with the adjuster it is located under the cover plate 21 which has to be removed by manipulation of the thumb and finger studs 19 in order to uncover the hole through which the adjusting tool 26 is to be inserted. This tool is to be in the custody of the foreman whose directions as to the number and arrangements of the tacks is to be followed. A similar arrangement for delivering one or another of a plurality of tacks to a toe tacker having two or more drivers might be employed but to save space and duplication of parts and to obtain other advantages the toe tacker is instead made laterally adjustable to insert a tack at or on either side of the median line of the machine and preferably in any one of many locations whereby it is adapted for operation on right and left shoes of more or less crookedness. To this end the toe tacker arm 35 which is hung upon the frame at 36 for inward and outward swinging is pivoted at 38 for lateral swinging movement. It is also transversely slotted at 40 to receive a cross bar 42 connecting the wide spread ends of the forward fork 88 of the mechanism by which it is actuated inwardly to tacking position and outwardly to position for clearance. This mechanism in other respects than the presence of this bar and the width of this fork may be the same as shown in Fig. 39 of my prior patent. The guideway in the machine head 2 through which the arm moves is also made wider than the arm and it is overlaid by a plate 45 in which the arm fits as to width but can move freely forwardly and backwardly. This plate has a laterally extended toothed arm 46 that is engaged by a segment rack 48 connected with a hand lever 50 in which a spring pin is held to engage a fixed ratchet plate 52 for locking the lever with the plate 45 and the toe tacker arm in laterally adjusted position. The conductor tube 12 for the fourth tack is secured to the tacker arm for adjustment with it, said tube being loosely connected to the raceway block to permit this movement. The toe gripper may have its bar 60 guided in the plate 45, as shown in Fig. 2, for lateral movement with the toe tacker and the toe wiper 62, which lays the upper upon the shoe innersole and holds it while the gripper releases and gives place to the tacker, is also adjusted with the tacker. By this latter provision the wiper may be positioned to wipe the upper squarely over the point of the toe or at right angles to the edge of the last so that it is laid in the proper position under the tack from the laterally adjusted tacker.

In the use of the machine, the toe and side grippers seize and pull the upper as usual, the pairs of jaws of the double side grip-

pers moving relatively to pull the upper down into the low position of the last back of the high toe if this shape of last is in use. If the adjustment of the plates 22, 23 is as shown in Fig. 4, seven tacks will be driven including the second and sixth tacks for holding the upper tight over the rear of the toe, and including the first and seventh tacks for holding the upper under tension over the rear of the ball. If the latter holding effect is not desired, as may be the case in some shoes, the Fig. 5 adjustment is made to cut out the first and seventh tacks. If on the other hand the intermediate tacks are not required, the Fig. 6 adjustment will discontinue the delivery of the second and sixth tacks. It is obviously undesirable to have the machine drive superfluous tacks because all the pulling-over tacks have to be removed from all welt shoes and they are taken out from McKay shoes to a large extent for the lasting operation. The toe tacker is adjusted for the shape for the last that is in the machine and with it is also adjusted the toe wiper and the toe gripper. This adjustment can be made at any time, either before the machine is started, or initially, or supplementally while the gripper holds the upper.

Having explained the nature of this invention and described a preferred construction embodying the same, I claim as new and desire to secure by Letters Patent of the United States:

1. A pulling-over machine having, in combination, means for positioning a shoe, gang means for inserting a plurality of tacks into each side of the shoe, and means which can be set to locate the tacks that are to be driven on the same side of the shoe in one or another of certain definite spaced relations to each other, said relative locations being predetermined by the construction of the machine.

2. A pulling-over machine having, in combination, means for positioning a shoe, means for inserting a tack at the toe of the shoe, means for inserting a plurality of tacks at each side of the toe, and a single means adapted for adjustment to suppress the insertion of certain of the side tacks at both sides of the shoe without similarly affecting the remaining tacks.

3. A pulling-over machine having, in combination, means for positioning a shoe, means for inserting a tack at the toe of the shoe, means for inserting a plurality of tacks at each side of the toe, and a single means arranged for adjustments by which to suppress alternatively one or another of two of the side tacks.

4. A pulling-over machine having, in combination, means for positioning a shoe, means for inserting a tack at the toe of the shoe, means for inserting a plurality of tacks

at each side of the toe, including mechanism for supplying tacks to said tacking means, and a single means adjustable to control the delivery of specified tacks of a plurality of the series without similarly affecting the delivery of other tacks of the series. 70

5. A machine of the class described having, in combination, means for driving tacks at the opposite sides and at the toe end of a shoe, and means adapted by a single adjustment to suspend the insertion of one of the tacks at each side of the shoe. 75

6. A machine of the class described having, in combination, means for driving tacks at the opposite sides and at the toe end of a shoe, and means adapted by different adjustments to suspend the insertion of one or another of a plurality of tacks for the same side of the machine. 80

7. A machine of the class described having, in combination, means for driving seven tacks including one tack located at the toe of a shoe and three tacks located at each side of the shoe, and a single adjusting means to suspend and resume the insertion of the rear tack on both sides of the shoe. 85

8. A machine of the class described having, in combination, means for driving seven tacks including one tack located at the toe of a shoe and three tacks located at each side of the shoe, and means capable of one adjustment to suspend the driving of the rear tack on each side of the shoe and of another adjustment to resume the insertion of the rear tacks and discontinue the insertion of the intermediate tack on each side. 95

9. A machine of the class described having, in combination, means for driving seven tacks including one tack located at the toe of a shoe and three tacks located at each side of the shoe, a single means capable of adjustment to suspend the insertion of one or another of the side tacks, and means to shift the lateral relation of the toe tack to the side tacks. 105

10. A pulling-over machine having, in combination, means for positioning a shoe, means for inserting a tack at the toe of the shoe, means for inserting side tacks, and an adjuster for suppressing the insertion of a tack on one side of the shoe and causing a previously suppressed tack on the other side to be inserted. 110

11. A machine of the class described having, in combination, means for supplying and inserting a gang of tacks including a plurality of raceway grooves and multiple tack separating and delivering mechanism, and a plurality of connected stops arranged for manual adjustment simultaneously to 120 discontinue the presentation of tacks in different grooves alternatively and cause the machine to supply and insert tacks from the same group of raceways during successive operations. 125

- 4 12. A machine of the class described having, in combination, a raceway block 20 having a plurality of tack grooves thereon, the tack-separating slide 10 coöperating with the several grooves, and the adjustable stop plates 22, 23 having tack passages therethrough and mounted for movement to place said passages in or out of alignment with tack grooves.
- 10 13. A machine of the class described having, in combination, the adjustable stop plates 22, 23, the adjuster 25 connected with both plates, and means for manipulating the adjuster.
- 15 14. A machine of the class described having, in combination, tack supplying and feeding mechanism, the stop plates 22, 23 adapted to shut off the presentation of certain of the tacks, the adjuster 25 connecting the overlapping ends of the plates and having a screw threaded shank, and the worm rod 26 for rotating the adjuster.
- 20 15. A machine of the class described having, in combination, means for driving tacks at the opposite sides and at the toe end of a shoe, and means adapted for effecting transverse movement of the toe tacker in the machine and for fixing the toe tacker in different adjusted positions transversely of the machine for the purpose described.
- 25 16. A machine of the class described having, in combination, tackers for the sides of a shoe, a tacker for the toe of the shoe having a wiper to lay the upper into position to be secured, and means permitting adjustment of the toe tacker and wiper transversely to positions for the wiper to act substantially perpendicularly to the toe end face of right and left lasts.
- 30 17. A pulling-over machine having, in combination, a tacker movable in and out over the shoe bottom substantially perpendicularly to the adjacent edge face of the shoe and adapted to insert a plurality of tacks spaced along the shoe edge, and means adapted for adjustment without altering the position of the tacker as a whole, to determine the position along the shoe edge at which tacks shall be inserted by the operation of said tacker.
- 35 18. A pulling-over machine having, in combination, gang side tackers and a toe tacker, means for suspending the insertion of one tack from each side tacker, and means for adjusting the toe tacker to cause it to insert a tack nearer to one than the other side tacker.
- 40 19. A pulling-over machine having, in combination, gang side tackers, and a toe tacker, and means for determining simultaneously for both side tackers one or another of a plurality of positions in which side tacks shall be inserted with relation to the toe of the shoe.
- 45 20. A pulling-over machine having, in combination, gang side tackers and a toe tacker, means arranged for adjustment to effect predetermined relative positioning of the side tacks lengthwise of the adjacent portion of the last edge, and other means arranged for adjustment to cause a toe tack to be inserted in different positions lengthwise of the portion of the last edge that is adjacent to the toe tacker.
- 50 21. A machine of the class described having, in combination, gang tacking mechanism supplied with tack raceways and drivers, and one means associated with a plurality of raceways and capable of adjustment for selectively determining which raceways less than the whole number shall deliver tacks and thereby determining the arrangement of the tacking affected by the mechanism while all the drivers may continue operative.
- 55 22. A pulling-over machine having, in combination, side tackers each of which is arranged to insert a plurality of tacks along the side of a shoe, means for supplying tacks to said tackers, and one controlling means adapted by different adjustments to discontinue the insertion of one or another of a plurality of tacks at the same side of the shoe.
- 60 23. A pulling-over machine having, in combination, side tackers each of which is arranged to insert a plurality of tacks substantially simultaneously along the side of a shoe, means for supplying tacks to said tackers, and a single adjusting means adapted to control one or the other of two tacks located at the same side of the shoe.
- 65 24. A pulling-over machine having, in combination, side tackers each of which is arranged to insert a plurality of tacks substantially simultaneously along the side of a shoe, means for supplying tacks to said tackers, and means adjustable transversely across a raceway in a direction at right angles to the length of the tack stems for closing and opening the raceway to the passage of tacks.
- 70 25. A pulling-over machine having, in combination, side tackers each of which is arranged to insert a plurality of tacks along the side of a shoe, means for supplying tacks to said tackers, and means located between two raceways adapted for adjustment transversely across one or the other of said raceways or to occupy an intermediate position in which both raceways are open.
- 75 26. A machine of the class described having, in combination, gang mechanism for supplying and distributing tacks including a raceway structure having a plurality of tack grooves and a multiple tack separator, and a multiple tack stop adapted for alternative adjustments to discontinue the progress of tacks in one or another of the tack grooves.

27. A machine of the class described having, in combination, gang mechanism for supplying and distributing tacks including a raceway structure having a plurality of 45
5 tack grooves and a multiple tack separator, and a tack stop arranged to be projected transversely across a tack groove below the heads of the tacks in a direction at right angles to the stems of the tacks.
- 10 28. A machine of the class described having, in combination, a raceway structure having a plurality of tack grooves and a tack controller having a passageway 24 spanning two grooves and the intervening portion 50
15 of the raceway structure and having opposed fingers 24^a, 24^b located below the tack head supporting surfaces of the raceway structure in position to be projected across the tack grooves in the path of the 55
20 tack stems to close one or the other raceway in alternative adjustments thereof.
- 25 29. A machine of the class described having, in combination, a raceway structure having a plurality of tack grooves and a tack controller having a passageway 24 spanning two grooves and the intervening portion 60
30 of the raceway structure and having opposed fingers 24^a, 24^b located below the tack head supporting surfaces of the raceway structure in position to be projected across the tack grooves in the path of the 65
35 tack stems to close one or the other raceway in alternative adjustments thereof, said fingers being spaced far enough apart to have both grooves open in an intermediate adjustment thereof.
- 40 30. A machine of the class described, having, in combination, a raceway structure having a plurality of tack grooves and tack controllers for opposite sides of the machine, said controllers having their ends over- 70
45 lapped, an oscillatory connector having engagement above its center with one controller and below its center with the other controller and means for adjusting the connector.
31. A machine of the class described, having, in combination, a raceway structure having a plurality of tack grooves and tack controllers for opposite sides of the machine, 50
55 said controllers having their ends overlapped, an oscillatory connector having engagement above its center with one controller and below its center with the other controller and a worm and screw by which the connector can be adjusted and is automatically maintained in adjusted position.
32. A machine of the class described, having, in combination, with shoe supporting means, a tacker which is mounted to move inwardly over the shoe bottom from a tack receiving position to a tack delivering position and is also mounted for swinging movement transversely of the direction of the 60
65 first mentioned movement.
33. A machine of the class described, having, in combination, a tacker adapted for movement from a tack receiving position to a tack delivering position over a shoe bottom and supporting means on which the tacker is mounted to swing about two axes extending transversely to one another and substantially perpendicularly to the plane of the tack inserting movement.
- In testimony whereof I have signed my 75
name to this specification in the presence of
two subscribing witnesses.
